UNITED STATES PATENT OFFICE.

REUBEN C. BAKER, OF COALINGA, CALIFORNIA.

CALF AND BULL WHEEL BEARING.

1,155,539.

Specification of Letters Patent.

Patented Oct. 5, 1915

Application filed May 15, 1913. Serial No. 767,886.

To all whom it may concern:

Be it known that I, REUBEN C. BAKER, a citizen of the United States, residing at Coalinga, in the county of Fresno and State of California, have invented a new and useful Calf and Bull Wheel Bearing, of which the following is a specification.

This invention relates to improvements in bearings and more particularly in bearings 10 for bull wheels which are used in connection with drilling apparatus.

An object of the present invention is to provide a bearing with the front cap thereof removably secured to the base of the bearing 15 and to further provide a recess in the front cap whereby a suitable compression member may be inserted thereagainst to successfully take up the forces which are exerted by the bull wheel during the drilling 20 operation.

With the foregoing and other objects in view which will appear as the description proceeds, the invention resides in the combination and arrangement of parts and in 25 the details of construction hereinafter described and claimed, it being understood that changes in the precise embodiment of the invention herein disclosed, can be made within the scope of what is claimed, without 30 departing from the spirit of the invention.

In the drawings accompanying this specification and forming a part thereof, the preferable form of my invention is illustrated, in which:—

35 Figure 1 is a vertical cross sectional view of my improved bull wheel bearing. Fig. 2 represents a top plan view thereof. Fig. 3 is a diagrammatic view showing my improved bull wheel bearing in elevation and 40 the manner in which the same is secured to the supporting structure therefor.

Referring to the drawings in which similar reference numerals designate corresponding parts throughout the several views, 1 45 is the body portion of the pillow or bearing block and 2 are bosses outstanding therefrom and through which extend the apertures 3, the same forming means whereby the bull wheel bearing may be rigidly secured to a supporting structure.

The said body portion is provided with the semicircular openings 4 extending transversely thereof and the cap receiving surface 5 of the body portion intersecting the said 50 opening upon a diametric line and with the plane thereof extending at an acute angle

to the bottom of the body portion. The said cap receiving surface of the body portion is provided with the upstanding shoulders 6—6, adjacent the ends thereof and which shoulders are adapted to hold the cap 7 against relative motion with respect to the body portion.

The detachable cap 7 is provided with the semi-circular opening 8 extending therethrough, the same being adapted to register with the semi-circular openings 4 of the body portion to thereby form a suitable bearing for the bull wheel shaft to pass through and be rotatably supported thereby.

The cap 7 is of a size adapted to fit between the shoulders 6—6 of the body portion and in order to further secure the cap thereto, suitable apertures extend therethrough and are adapted to be engaged by the stud 75 bolts 9, the latter threadedly engaging the body portion 1. In order to rigidly hold the cap in position, the nuts 10 threadedly engage the outer portions of the stud bolts 9 and are adapted to contact with the outer 80 surface of the cap and to be tightened thereagainst. Arranged parallel to the meeting faces of the cap and the body portion is the milled surface 11 provided with suitable upstanding shoulders 12 at the side edges 85 thereof. The milled surface 11 is positioned directly above the semi-circular opening 8 of the cap and is adapted to receive a compression post or member thereagainst and to prevent the displacement thereof.

As illustrated in Fig. 3 of the drawings, a compression member or post 13 is rigidly secured to the supporting structure and is positioned with the end thereof within the recess defined by the surface 11 and the upstanding shoulders 12. As is well known in the drilling art, when the cable is wound upon the bull wheel and released, that during said drilling operation, a certain force will be exerted upon the bull wheel bearing 100 in an upward and outward direction in alinement with the rope or cable to which the drill is attached. Therefore, with the bearing as I have described it, the outward force will be successfully taken up by the 105 compression member 13 acting directly against the outer surface of the cap to which it is held to thereby relieve the stud bolts 9 and tightening nuts 10 of any direct force other than produced by the tightening of 110 the nuts to secure the cap in position. The horizontal force will be successfully taken

up by the body portion of the pillow or bearing block and transmitted to the base thereof which is rigidly secured to the supporting structure by suitable bolts passing through the openings 3 therein. Although no lining has been illustrated as positioned within the opening defined by the semi-circular portions 4 and 8, it will be understood that suitable babbitt or brass sheets may be inserted therein. The bearing herein described is particularly adapted to support a bull wheel which will be subject to the stress such as I have described.

Having thus fully described the invention, what I claim to be new and original with me is:—

In well drilling machinery, the combination with an upstanding supporting structure and a laterally extending structure fixed relative thereto, of a bearing block secured to one side of the upstanding structure and provided with an inclined active face formed with a recess for the reception

of a revoluble element, a cap secured upon the recessed face of the bearing block and having a recess registering with the recess in said face of the block, thus to form a circular opening for the reception of a revoluble element, said cap having a recess in its outer or inclined upper face, and an upwardly and laterally inclined compression member bearing at one end within said last named recess within the cap and at its other end against the horizontally extending fixed structure, said member constituting means for reinforcing the cap against upward and outward pressure and constituting means for binding the bearing block against the upstanding supporting member.

In testimony that I claim the foregoing as my own, I have hereto affixed my signature in the presence of two witnesses.

REUBEN C. BAKER.
